James L. Morris

UNITED STATES PATENT OFFICE.

ELLEN ANN ANDERSON, OF EAST FREMANTLE, WESTERN AUSTRALIA, AUSTRALIA.

HOOK-AND-EYE FASTENER FOR TEXTILE MATERIALS.

Application filed September 26, 1923. Serial No. 665,001.

To all whom it may concern:

Be it known that I, ELLEN ANN ANDERSON, a subject of the King of Great Britain, residing at 31 Hubble Street, East Fremantle, Western Australia, Commonwealth of Australia, have invented certain new and useful Improvements in Hook-and-Eye Fasteners for Textile Materials, of which the following is a specification.

10 This invention provides a hook and eye fastener for wearing apparel and analogous uses—said fastener being adapted to be securely attached to the garment or material without the aid of sewing or stitching, thereby saving time and incidental monetary outlay. The invention comprises a hook member and an eye member each of which is hingeably secured to a base plate formed with retention teeth whereby said plate and thereto attached hook or eye is secured and anchored to the garment or material for use and service in the usual and well known manner.

The construction and use of my invention will be clearly set forth with the aid of the attached perspective drawings wherein Fig. 1 shows the base plate separate from its hook member proper. Fig. 2 shows said hook member. Fig. 3 shows the base plate separate from its eye member proper. Fig. 4 shows the eye member. Fig. 5 shows the hook member hingeably conjoined with its base plate and attached to the material, and Fig. 6 shows the eye member hingeably conjoined to its base plate and attached to the material. In said drawings the hook and eye members, together with their base plates are enlarged approximately four times their normal size.

40 Referring to the drawings in detail, Figs. 1, 2 and 5 illustrate the hooked member and its associated parts, the first two figures showing the parts disassembled and Fig. 5 showing the parts assembled and connected to a fabric or the like. It will be observed by referring to Fig. 1 that I provide a plate *a* having at one end a pair of tines or prongs *d* and at the opposite end a pair of ears *b* connected by a pin *c* spaced from the plate member *a*. The hook member proper comprises a pair of parallel shanks *g* having eyes *f* at one end and connected at their other ends by means of a loop rebent upon the shanks *g* forming loops at *j* and providing a hook. The eye member of the combination is illustrated disassembled

in Figs. 3 and 4 and assembled with a strip of cloth or the like in Fig. 6. The eye construction comprises a plate member *k* having tines *p* at one end and ears *m* at the opposite end, the plate *k* being T-shaped and the ears located at the ends of the cross member of the T. The ears are connected as in the case of the ears *b* on the plate *a* by a rod or pin *n* spaced from the plate *k*. Cooperating with the plate *k* is an eye member *t* provided with eyes *s* at one end and formed in a loop at the other end, the two legs of the loops being connected by a tubular member *x* adapted to receive therethrough the pin *n*. The plate *a* is assembled with the hook member by slipping the rebent loops under the pin *c* upon which the hook member may pivot in assembling the hook with a strip of cloth or the like. When the hook and strip are brought into position on opposite sides of the cloth, the hook member may be rocked on the pin *c* as a pivot, bringing the eyes *f* down upon the tines *d*, which are projected through the fabric, whereupon the ends of the tines may be bent outwardly as shown in Fig. 5, thus securely fastening the hook to the cloth and bracing the cloth between the shanks *g* and the plate *a*.

When the eye member *t* is connected to the plate, the said eye member may be rocked upon the pin *n*, so that the cloth to which it is to be attached may be passed through the eye member and its accompanying plate, and as in the case of the hook member, the eyes may then be brought down upon the tines, which are projected through the cloth and bent outwardly to secure the eye in place upon the cloth.

It will be noted that by this construction I am enabled to securely fasten the hook and eye of a combination to their respective parts of a garment without stitching and in such a manner that they will be held in a proper position on said cloth for being readily hooked one into the other.

What I claim as my invention and desire to secure by Letters Patent is:—

1. A fastening device for garments, comprising a plate having tines at one end thereof and ears at the opposite end, a pin connecting said ears and spaced from said plate, a hook proper having eyes adapted to align with said tines and having a portion thereof extending between said pin and plate.

2. In a fastening device for garments and

the like, a plate having tines at one end and ears at the opposite end, a pin connecting said ears and spaced from said plate, an eye member having eye portions adapted 5 to align with said tines, and a loop having a tubular member attached thereto and adapted to receive said pin.

3. In a hook and eye arrangement, a plate, and a fastening member hinged thereto adjacent one end, the opposite end of said plate 10 having tines for securing the fastening member and the plate to a garment or the like.

4. A hook and eye combination comprising

ing plates having tines thereon at one end and ears at the opposite end, hook and eye 15 members each respectively associated with one of said plates and secured to a fabric or the like and its respective plate by means of said tines, and a pivot pin connecting said ears and forming a pivot for the associated hook or eye member as the case may be.

In testimony whereof I have hereunto set my hand.

ELLEN ANN ANDERSON.
